UNITED STATES PATENT OFFICE.

ROSS G. YOUNT, OF CALWA CITY, CALIFORNIA.

SELF-CLOSING BLEED COCK FOR AIR BRAKES.

Application filed September 2, 1924. Serial No. 735,453.

To all whom it may concern:

Be it known that I, Ross G. YOUNT, a citizen of the United States, residing at Calwa City, in the county of Fresno and State of California, have invented certain new and useful Improvements in Self-Closing Bleed Cocks for Air Brakes, of which the following is a specification, reference being had to the accompanying drawings.

10 This invention relates to bleed cocks for air brake cylinders.

The ordinary bleed cock which is used in connection with an air brake cylinder only remains open so long as the operator holds the cock open, which he does until the brakes are released.

20 The object of the present invention is to provide a bleed cock for air brakes which will be held open for a certain length of time and will then automatically close and return to its original condition.

A further object is to provide a device of this character which is very simple, can be readily operated, cheaply made, and 25 readily applied.

Other objects will appear in the course of the following description.

My invention is illustrated in the accompanying drawing, wherein:—

30 Figure 1 is a vertical sectional view through a bleed cock constructed in accordance with my invention;

Figure 2 is an elevation of the bleed cock partly broken away;

35 Figure 3 is a fragmentary sectional view through the stem 20, the wall or flange 16 being in elevation;

Referring to these drawings, 10 designates the body of the bleed cock, which is 40 approximately cylindrical in form, and is provided at one end with a screw-threaded extremity 11 and at the other end with a cap 12 having an interiorly screw-threaded flange 13 adapted to engage with the extremity of the body 10. At one end the body 10 is formed with a chamber 14 closed by the cap 12. The lower end of this chamber is defined by a wall 15 having a central aperture 16. Disposed within the 45 chamber 14 is a valve 17 having a downwardly extending stem 18 which passes loosely through the aperture 16.

Mounted in a bearing in the side wall 19 of the body below the wall 15 is a spindle 20 which carries upon it inside the chamber 21 the disk 22 having a circular opening

23 eccentric to the center of the disk. The disk itself is eccentrically mounted upon the spindle 20. Extending from the stem 18 is a pin 24 which extends into the opening 23, the pin being much smaller than the opening, as shown in Figure 2. Mounted upon the exterior of the spindle 20 is a lever 25, the lower end of which is weighted, as at 26, and the upper end of which is pivoted to a pull rod 27 whereby the lever may be operated. It will be understood, of course, that the disk 22 is fast upon the spindle 20 and oscillates therewith. The chamber 14 has leading from a point above the wall 15 a duct 28 which extends downward through the side wall of the body 10 and down through the nipple 11.

The cap 12 has mounted thereon a downwardly extending bracket 29 upon which is pivoted a lever 30, one end of this lever having a depending weighted portion 31, the other end of the lever being longitudinally slotted. The cap 12 is formed to provide an air duct 32 extending out through the side wall of the cap, and operating within this air duct is a needle valve 33, the lower end of which is engaged by a pin 34 with the lever 30. When the weighted end 31 of the lever 30 is depressed by the weight 31, the needle valve closes the duct of the port 32, while when the weighted end of the lever is raised the needle valve 33 permits the discharge of air from the chamber 14.

It will be understood, of course, that this bleed valve or cock is connected to the auxiliary reservoir and that, therefore, when the valve 17 is lowered to its seat the pressure of air within the reservoir holds the valve 17 closed and thus the air is retained within the cylinder. When, however, it is desired to "bleed a car and let all the air pressure escape out of the train line pipes and brakes," the trainman operates the pull rod 27, which acts to rotate the lever 25 and the disk 22 and the wall of the circular aperture of the disk engages the pin 24 and acts to lift the stem 18, thus lifting the valve 17 from its seat. After the valve 17 has moved upward a certain amount, it strikes the depending end 31 of the lever 30 and pushes this end of the lever upward, withdrawing the needle valve from the duct 32 and permitting the escape of the air from the auxiliary reservoir through chamber 14. As soon as this has occurred, the

pull rod may be released, but as long as there is any air pressure in the chamber 14 the valve 17 will be held up and thus the valve 33 will be held open. When the air pressure has been entirely released, however, the valve 17 drops and this permits the weighted end of the lever to descend, causing the closing of the needle valve 33. Thus it is not necessary for the trainman to hold the cock open until all of the pressure in the train line has been released and it is merely necessary to hold the valve 17 closed to its full extent and then lift it and the air pressure will be gradually relieved until it is reduced to atmospheric pressure, when the valve 17 will drop to its normal position.

If a train arrives at a station and has several cars to set out on several different tracks, the practice is to first "bleed" the cars so that the brakes will not stick while switching. With the present style of bleeder, the trainmen are compelled to hold the bleed cock open until the car is bled, which takes from one to five minutes with each car. With my improved bleed cock, all that would be necessary would be to open the bleed cock and then the trainman passes on to the next car and the bleed cocks would eventually close themselves after the car was bled, thus saving from two to four minutes for each car. Oftentimes a trainman will block a bleeder open with a stick or stone and leave it to go on to the next car, or they will pull the pull rod out as far as possible and bend it downward outside of the guide to prevent the rod from slipping back and closing the bleed cock. The result is that when the car is again picked up by some train and the air pressure put into the train, there will be a leak at the bleed cock, sometimes for an hour or more before a trainman will discover it, or before he will be on that side of the car to release the pull rod. This causes low train line pressure and ineffective brakes.

This is entirely prevented with my bleed cock for the reason that it automatically resets itself as soon as all of the pressure has been relieved. Most of the station switching is done by local freights and it is on these freight trains that the ordinary bleed cock causes particular trouble. The time lost by the average trainman in bleeding the cars is from fifteen minutes to an hour a day, and assuming that fifteen minutes is used by each man of a train crew of five, it will be obvious that there will be a loss of seventy-five minutes per day. It will be obvious that the saving of seventy-five minutes a day for each train crew will amount to a very large saving in the course of the year, even if the time for operating the bleed cocks is reduced only one-half.

While I have particularly designed this valve for use with air brakes, I do not wish

to be limited thereto as it is obvious that it might be used for a variety of other purposes, nor do I wish to be limited to the exact construction illustrated as this might be changed in many ways without departing from the spirit of the invention as defined in the appended claims.

I claim:—

1. A bleed cock of the character described including a body having a chamber formed therein, there being a duct leading from the interior of the chamber to one end of the body, a valve disposed in said chamber, the chamber having an outlet opening, means normally closing said outlet opening, manually operable means for lifting the valve, said manually operable means automatically returning to its normal position without affecting the lifted valve, and means acted upon by the lifting of the valve permitting the escape of air through said outlet opening and acting upon the descent of the valve to close said outlet opening. 75

2. A self-closing bleed cock for air brakes comprising a body formed at one end for engagement with an air brake system, the opposite end of the body being formed with an air chamber, there being a duct leading from the first named end of the body into said air chamber, a wall forming the lower end of said chamber and having a passage, a valve disposed within the first named chamber and having a stem extending downward through said passage, manually operable means carried by the lower end of the body and adapted to be shifted from its normal position to lift the valve and automatically return to its normal position without affecting the lifted valve, the chamber having an outlet port, a valve normally closing said port, and means actuated by the lifting of the first named valve acting to shift the second named valve from its seat. 95

3. A bleed cock of the character described including a body formed at one end for engagement with an air brake system, the opposite end of the body being formed with an air chamber, there being a duct leading from the first named end of the body into said air chamber, a wall forming the bottom of the chamber and having a passage, a valve disposed within the first named chamber and having a stem extending downward through said passage, said valve being normally disposed below the outlet of the first named duct, a pin projecting from the stem, a member disposed within the lower chamber and having an aperture into which said pin projects, the aperture being larger than the pin, manually operable means upon the exterior of the valve for oscillating said member, and means within the chamber acted upon by a lifting of the valve for establishing communication between the interior of the chamber and the outside air. 110 115 120 125 130

4. A self-closing bleed cock for air valves comprising a body formed at one end for engagement with an air brake system, the opposite end of the body being formed with an air chamber, there being a duct leading from the first named end of the body into said air chamber, a wall defining the lower end of the chamber and having a passage, a valve disposed within the first named chamber and having a stem extending downward through said passage, the upper end of the chamber being formed with an air outlet port, a valve normally closing said port, a lever pivotally mounted within the chamber and having one end engaged with said valve, the opposite end having a depending weighted portion adapted to be engaged by the first named valve when the valve is fully raised to thereby open the second named valve, and manually operable means for lifting the first named valve from its seat, said means permitting the first named valve to descend by its own weight.

5. A self-closing bleed cock for air brakes comprising a body formed at one end with a reduced screw-threaded extremity for engagement in an air brake system and at the other end for screw-threaded engagement with a cap, a cap closing the last named end of the body and having an air outlet port formed therein, a valve for closing said port, a lever mounted upon the cap and disposed within the chamber and at one end engaging the valve, the other end of the lever having a depending weighted portion, the body being formed with a longitudinally extending duct leading from the first named end of the body and into said chamber, the

lower wall of the chamber having a passage, a valve seating on said lower wall and having a depending stem extending through said passage, the valve being normally disposed below the outlet of said duct, and manually operable means for raising said second named valve, said means permitting the second named valve after it is raised to descend under its own weight.

6. A self-closing bleed cock for air brake cylinders comprising a body having a chamber formed therein, there being a duct leading from the interior of the chamber to one end of the body, the lower end of the chamber having a passage, a valve disposed in the chamber and normally below the inlet of said duct and having a screw extending downward through said passage, means in the upper end of the chamber whereby when the valve is raised communication may be established between the outside air and the interior of the chamber and said communication disestablished when the valve is lowered, manually operable means for raising the valve including a pin projecting laterally from the projecting stem of the valve, a spindle extending through a side wall of the body, a disk eccentrically mounted upon the spindle and having an opening into which said pin projects, the pin being smaller than the opening, and a lever mounted upon said spindle on the exterior of the body, the lever having means at one end whereby it may be operated and being weighted at the other end.

In testimony whereof I hereunto affix my signature.

ROSS G. YOUNT.
